UNITED STATES PATENT OFFICE.

CHRISTOPHER H. WAGNER, OF ELKHART, INDIANA, ASSIGNOR OF ONE-THIRD TO WILLIAM KLINE, OF TOLEDO, OHIO.

DEVICE FOR ATTACHING CROSS-BARS TO TELEGRAPH-POLES.

SPECIFICATION forming part of Letters Patent No. 291,435, dated January 1, 1884.

Application filed April 19, 1883. (No model.)

To all whom it may concern:

Be it known that I, CHRISTOPHER H. WAGNER, a citizen of the United States, residing at Elkhart, in the county of Elkhart and State of Indiana, have invented a new and useful Device for Attaching Cross-Bars to Telegraph-Poles, of which the following is a specification, reference being had to the accompanying drawings.

10 This invention relates to an improved device for attaching the cross-arms to telegraph-poles; and it has for its object to avoid the necessity of cutting notches in the poles for the reception of said cross-bars, as is usually practiced, and whereby the poles are greatly weakened.

To this end the invention consists in the improved construction of certain clamps or holders, as will be hereinafter fully described, 20 and particularly pointed out in the claims.

In the drawings hereto annexed, Figure 1 is a top view of my invention applied to a telegraph-pole. Fig. 2 is a front view of the cross-arm with the clamps attached. Fig. 3 is a side view of the same. Fig. 4 is a front view of one of the clamps or holders. Fig. 5 is a side view of the same, and Fig. 6 is a section on the line *xx* in Fig. 4.

The same letters refer to the same parts in the several figures.

A A in the drawings represent the clamps or holders which constitute my invention, and of which two are used for each cross-arm which is to be secured to the pole. The said clamps or holders consist of plates wedge-shaped in cross-section, as clearly shown in Fig. 6 of the drawings, their outer ends or edges being the thickest. The upper and lower ends of said plates are provided with 40 forwardly-projecting flanges B B, between which the cross-arm C is fitted, as shown. The plates A A are provided with horizontal slots D D, to receive the fastening bolts or spikes E E, and their rear sides (or the sides 45 adjoining the pole) are provided near their

outer edges with rearwardly-projecting sharp-pointed lugs or barbs F F.

G represents the telegraph-pole.

The operation of the invention will be readily understood from the foregoing description, taken in connection with the drawings hereto annexed. The fastening bolts or spikes pass through the cross-arm, through the slots D in the plates A, and into the pole, to which the clamps and cross-arm are thus secured. By 55 tightening the bolts or spikes, the lugs or barbs F are drawn into the pole, to which the cross-arm is thus attached securely against vertical displacement. By this construction and arrangement of parts the cross-arms are 60 enabled to support the strain and weight of the wires, and, when occasion requires, of the repair-man, without strain upon the bolts and without weakening the poles by cutting notches in them for the reception of the cross-arms. 65

I claim as my invention and desire to secure by Letters Patent of the United States—

1. The herein-described clamps or holders for attaching cross-arms to telegraph-poles, the same consisting of wedge-shaped horizontally-slotted plates having rearwardly-projecting sharp-pointed lugs or barbs and forwardly-extending flanges at their upper and lower ends, substantially as set forth. 7c

2. The combination, with a telegraph-pole, 75 of a pair of clamps or holders, consisting of wedge-shaped horizontally-slotted plates having rearwardly-projecting sharp-pointed lugs or barbs and forwardly-extending flanges at their upper and lower ends, a cross-arm fitted 80 between said flanges, and fastening bolts or spikes, substantially as and for the purpose set forth.

In testimony that I claim the foregoing as my own I have hereto affixed my signature in 85 presence of two witnesses.

CHRISTOPHER H. WAGNER.

Witnesses:

WILLIAM D. MIDDLETON,
JOHN F. GRUBB.
